UNITED STATES PATENT OFFICE

JOHN H. HANLON, OF SOMERVILLE, AND JOHN W. HANLON, OF MILTON, MASSACHUSETTS, ASSIGNORS TO HANLON LOCOMOTIVE SANDER COMPANY, OF WINCHESTER, MASSACHUSETTS, A CORPORATION OF MASSACHUSETTS

TRACK SANDER

Application filed June 8, 1929. Serial No. 369,311.

This invention relates to track sanders for locomotives and the like, and especially to sanders of the pneumatic type, in which air under pressure is employed to draw the sand 5 from a sand box or other supply chamber or reservoir and cause it to fall into a discharge pipe leading to the rear.

Track sanders of this general type include a fitting providing an air passage and a sand 10 passage. A pair of air nozzles communicating between the air and sand passages, one being positioned to throw a jet of air into the sand reservoir to loosen the same, and the other being positioned to throw a jet of 15 air into the outlet of the sand passage and draw the loosened sand by suction through the sand passage to the outlet leading to the tracks.

Normally closed clean-cut openings are provided in the sand passage and have at times 20 been utilized to gain access to the air nozzles to clean the same by running a wire or the like into the nozzle from the sand passage end thereof. This often has resulted in 25 wedging particles of sand in the nozzle and permanently clogging the same and rendering the sander inoperative and useless until special tools could be obtained for removing the air nozzle.

It is an object of the present invention to 30 overcome these difficulties by providing a construction in which the air nozzles are accessible readily from the air passage for cleaning or removal.

It is another object of the invention to 35 provide an improved sander in which the air nozzles are constructed and arranged to throw a light jet of air into the sand in the sand reservoir and a relatively powerful jet 40 of air into the outlet of the sand passage so that the sand is loosened by the former and withdrawn solely by the latter in controlled amounts.

Before explaining in detail the present invention, it is to be understood that the invention is not limited in its application to the details of construction and arrangement of parts illustrated in the accompanying drawings, since the invention is capable of 45 other embodiments and of being practised

or carried out in various ways. Also it is to be understood that the phraseology or terminology employed herein is for the purpose of description and not of limitation, and it is not intended to limit the invention beyond the terms of the several claims hereto appended as considered in view of the prior art and the requirements thereof.

The invention will be more clearly understood from the following description in conjunction with the accompanying drawings; in which,

Fig. 1 is a diagrammatic representation of a portion of a locomotive having applied thereto a track sander installation embodying the invention;

Fig. 2 is an enlarged plan view of the sander shown in Fig. 1;

Fig. 3 is an enlarged longitudinal section of the sander;

Fig. 4 is a plan view of the sander with the closure for the air passage removed; and

Fig. 5 is a sectional view taken upon the line 5—5 of Fig. 2.

In Fig. 1 is shown a portion of a locomotive having a boiler 10, a sand dome 11 and driving wheels 12 to which is applied a track sander indicated as a whole by the letter A. The sander A includes a fitting 15 providing a sand supply chamber or reservoir 16 with which communicates a sand supply pipe 17 leading from the sand box (not shown) located in the sand dome 11. A clean-out opening 18 is provided opposite the pipe 17 and is normally closed by a removable plug 19. A narrow substantially horizontal restricted sand passage 20 leads laterally from the chamber 16 and terminates in a relatively large, and preferably, inclined outlet 22 to which is connected a delivery pipe 23 leading to the rail. Clean-out openings 25 and 26 are provided in the fitting 15 at opposite ends adjacent the chamber 16 and the outlet 22 and are normally closed by removable plugs 27 and 28 respectively.

Above the narrow restricted sand passage 20 in the fitting 15 is provided a substantially horizontal air passage 30. The air passage 30 is connected with the sand passage by air ports or orifices, one of which is arranged

to discharge a relatively light jet of air into the sand in the sand chamber or reservoir, while the other is arranged to discharge a jet of air into the outlet 22 with such intensity as to withdraw sand by suction through the sand passage to the outlet 22. One of these air ports is provided with a nozzle 35 spaced from the sand chamber and arranged to throw a jet of air upon the sand in the sand supply chamber while the other is provided with a nozzle 36 arranged to throw a jet of air into the outlet 22. The passage 37 in the nozzle 35, preferably, is about half the size of the passage 38 in the nozzle 36. An air inlet 40 is provided in the fitting 15 communicating at one end with the air passage 30 and connected at the other end by a pipe 41 supplied with air under pressure from any suitable source under the control of the usual engineer's valve (not shown). Preferably, the inlet end of the nozzles 35 and 36 project inwardly from the wall of the air passage 30. The air passage is provided with an opening opposite the nozzles 35 and 36 and the air inlet 40 and normally is closed by a detachable cover 31 secured upon the fitting 15, as by screws 32. A clean-out opening 33 is provided in the cover 31 and normally is closed by a removable plug 34.

It will be understood that flow of sand through the sander to the rail is controlled by the admission of air under pressure through the pipe 41 and the air passage 30 by suitable operation of the engineer's valve. When the supply of air is cut off, the sand in the supply chamber 16 will assume approximately the position indicated in Fig. 3. When the air is turned on, a small jet is delivered by the nozzle 35 into the sand supply chamber to loosen the sand at the mouth of the restricted narrow passage 20 and a relatively strong jet is directed through the nozzle 36 into the outlet 22 thereby causing the loosened sand to be drawn solely by ejector action through the relatively restricted passage 30 to be mixed with air in the relatively large outlet 22 and discharged through the delivery pipe 23. By restricting the passage 20 a proper amount, it is possible to control the amount of sand drawn from the supply chamber 16 so as to avoid the discharge of an excess to the rails. The sand drawn through the passage 20 to the outlet is thoroughly mixed with air in the relatively large outlet 22 and the mixture is conveyed through the delivery pipe 23. In this manner clogging of the sand in damp or wet weather is avoided. By leaving one side of the air passage 30 open and normally closing the same by the cover 31, ready access to the air nozzles 35 and 36 is possible, for removal, without the use of special tools. In many cases it is possible to clean the nozzles 35 and 36 and the air inlet 40 by merely removing the plug 34.

We claim:

1. A track sander having a sand supply chamber, a sand passage leading therefrom to a discharge outlet, an air passage adjacent said sand passage adapted to receive air under pressure, an air nozzle connecting said passages, an opening in said air passage opposite said nozzle, an air supply inlet opposite said opening, a detachable closure for said opening, and a normally closed clean-out opening in said closure. 75

2. A track sander having a sand supply chamber, a sand passage leading therefrom to a discharge outlet, an air passage adjacent said sand passage adapted to receive air under pressure, an air nozzle connecting said passages and having a small orifice arranged to throw a relatively light jet of air on to the sand in said chamber, and an air nozzle connecting said passages and having a relatively large orifice arranged to throw a jet of air into said outlet with an intensity to create a suction in said sand passage to draw sand from said chamber to said outlet, an opening in said air passage opposite said nozzles, an air supply inlet to said passage opposite said opening, a detachable closure for said opening, and a normally closed clean-out opening in said closure. 50

3. A track sander having a sand supply chamber, a narrow substantially horizontal sand passage leading from the bottom of said chamber to a discharge outlet, an air passage adjacent said sand passage adapted to receive air under pressure, an air nozzle connecting said passages arranged to throw a jet of air across said sand passage directly into said outlet with an intensity to create sufficient suction to draw sand from said chamber to said outlet, and a relatively small air nozzle projecting from said air passage into said chamber to throw a jet of air on to the sand therein of an intensity insufficient to move sand to said outlet. 55

In testimony whereof we affix our signatures. 60
